UNITED STATES PATENT OFFICE.

DAVID HENRY ELKINS, OF AMESBURY, MASSACHUSETTS, ASSIGNOR TO GRAY & DAVIS INC., OF CAMBRIDGE, MASSACHUSETTS.

DESIGN FOR AN AUTOMOBILE-LAMP.

50,833.

Specification for Design.

Patented May 29, 1917.

Application filed August 18, 1915. Serial No. 46,215. Term of patent 7 years.

To all whom it may concern:

Be it known that I, DAVID HENRY ELKINS, a citizen of the United States, and resident of Amesbury, in the county of Essex and State of Massachusetts, have invented a new, original, and ornamental Design for Automobile-Lamps, of which the following is a specification.

Figure 1 is a view in side elevation of an automobile lamp embodying the new design.

Fig. 2 is a perspective view of the same.

Fig. 3 is a front view of a portion of the lamp.

I claim:

The ornamental design for an automobile lamp, as shown.

Signed at Amesbury in the county of Essex and State of Massachusetts this seventh day of August, A. D. 1915.

DAVID HENRY ELKINS.
